UNITED STATES PATENT OFFICE.

GAILLARD E. WEAVER AND ALBERT R. SQUYER, OF SPRINGFIELD, ILLINOIS, ASSIGNEES
TO WEAVER MANUFACTURING COMPANY, OF SPRINGFIELD, ILLINOIS, A CORPOR-
ATION OF ILLINOIS.

TRIP MECHANISM FOR JACKS.

Application filed July 14, 1926. Serial No. 122,349.

Our invention relates to lifting jacks, more particularly truck-jacks, and pertains especially to novel and improved tripping mechanisms therefor, whereby the appliance

5 may be easily operated to elevate the load or to cause its descent.

One aim of the invention is to provide a construction of this general character which is simple in structure, which can be easily 10 operated by the foot, and which works at least in part automatically, economy in manufacture and unlikelihood of becoming damaged or injured in ordinary service being also salient features of the new device.

15 To permit those trained in this art to have a full and complete understanding of the invention and its various advantages, in the accompanying drawings forming a part of this specification and throughout the several 20 views of which like reference characters have been employed to designate the same parts, a present desirable and preferred embodiment of the invention has been shown in detail.

25 In these drawings:

Figure 1 is a plan view of the truck-jack with the load-lifting parts in lowered position;

Figure 2 is a side elevation of the appliance with the members in the same position;

Figure 3 is a longitudinal section through the truck-jack with the cooperating elements in load-elevated positions;

35 Figure 4 is a similar section indicating the relation of the parts for lowering the load;

Figure 5 is an end elevation of the appliance;

40 Figure 6 is an enlarged section on line 6—6 of Figure 2;

Figure 7 is an enlarged horizontal section on line 7—7 of Figure 3;

45 Figure 8 is a detail view of the pawl and ratchet mechanism showing the parts in position for elevating the load; and

Figure 9 is a similar view illustrating the same parts in position for lowering the load.

50 Referring to the plurality of views of these drawings, it will be perceived that the truck-jack includes a horizontal main-frame, comprising an open, front, end casting 21, a rear

end casting 22, and spaced, parallel connecting-bars 23 and 24 bolted or otherwise secured to these two terminal members 21 55 and 22.

A cross-member 25, centrally pivoted or hinged to the casting 21 at 26, accommodates an axle 27 on the opposite ends of which are rotatably mounted a pair of carrying-wheels 60 28, 28, such element 25 at 29 having a pivotal connection with a comparatively-long link 30 rockingly mounted at its other end at 31 on a right-angle arm 32 pinned or bolted at 33 on the lower end of a tubular handle 34 65 rockingly mounted in a bearing-member 35 and having an appropriate top handle or cross-bar 36 at its upper end.

The bearing-member 35, at its lower end, is rockingly mounted on a cross-shaft 37 70 carried in bearings in spaced depending portions of the casting 22, whereby the handle 34 may be swung up and down in a vertical plane around the axis of the supporting shaft 37 and it may also be turned about its 75 own axis in the bearing-member 35, the latter capacity, as will be readily understood, being employed to effect the steering of the truck by the turning of the wheels 28, 28 through the medium of the connecting link 80 30.

The upward swinging or rocking movement of such handle is limited or restricted by reason of outstanding lugs 38, 38 on the bearing-member 35 engaging the end of the 85 adjacent casting 22, all as has been clearly illustrated, for example, in Figure 2.

The rear end of the truck-frame is supported by a double castor-wheel construction 39 mounted to swivel around a vertically- 90 disposed bolt 41, whereby the truck may be readily wheeled into any desired position by mere manipulation of the handle 34.

A saddle or seat 42 for engaging the load has a screw-threaded shank or stem 43 adjustable as to height in a threaded socket 44 forming part of a casting 45 constituting the end member of a lever comprising a pair of parallel bars 46, 47 riveted to the casting at 48, 48 and fulcrumed at the outer sides 95 of the main-frame bars 23 and 24 on aligned bolts 49, 51 extending through registering holes in the elements involved, the bar 47 being of sufficient length to extend an appre-

ciable distance beyond its fulcrum to a convenient position where it is fitted with a foot-piece or pedal 52.

Such lever casting 45 is connected by a link 53 to an extension of a ratchet-segment 54 fulcrumed on the casting 21 on a suitably-supported cross-shaft 55, such member 54 having ratchet-teeth on its substantially semi-circular periphery.

10 Obviously, the rocking or turning of the ratchet-segment will effect the raising or lowering of the lever 45, 46, 47, causing a corresponding elevation or descent of the saddle 42 and the load imposed on it.

15 To bring about the step by step turning of the ratchet-segment and a comparable movement of the load, the following specified cooperating instrumentalities are employed.

20 A bell-crank lever 56 is fulcrumed in the casting 21 on a cross-shaft 57 and the shorter, upper arm thereof has a pawl 58 rockingly mounted thereon and adapted to cooperate with the teeth of the ratchet-segment to produce the intermittent or step by 25 step action of the latter.

Such pawl or dog is yieldingly held to its work by a short, coiled spring 59 connected thereto at one end and to the casting 21 at the other end as is illustrated perhaps most 30 clearly in Figure 1.

The longer, depending arm of such bell-crank lever has a long link 61 pivotally connected thereto at 62, the opposite end of the link being similarly connected at 63 between 35 spaced ears to the bearing-member 35 hereinabove referred to.

40 A spring 64, encircling the link, bears at one end against an adjustable, screw-threaded member 65 on the link and presses at its other end against an abutment 66 forming part of the apertured casting 22, whereby the spring tends to hold the pawl or dog in elevated position ready to do its work when rocked downwardly.

45 Obviously, it is essential to have a holding dog or pawl to coact with the ratchet-segment during the retraction of the lifting pawl, and, accordingly, such an element 67 is provided and hinged or fulcrumed at 68 on the casting 21 being normally pulled up to its work, that is toward the companion segment, by a coiled, contractile spring 69 fastened thereto and to the casting.

55 Such holding or locking dog or pawl has a lateral lug 71 thereon in the path of movement of the end of a curved, cam arm 72 fulcrumed on the casting 21 at 57 and having an extension arm 73 connected to a link 74 slideable in aligned bearings in the spaced 60 arm 75 and 76 of a yoke 77 rigid with a flat bar 78 pivotally connected at 79 to the end of an arm 81 fixedly mounted on the inner end of a short shaft 82 rockingly accommodated in a bearing 83 forming part of 65 the casting 22, the outer end of such shaft

having a knurled, right-angle foot-piece or pedal 84 fixed thereon and having an adjustable abutment 85 in the plane of movement of the lever-bar 47.

Link 74 has a pin 86 extended therethrough and a coiled spring 87 encircles the link bearing at its rear end against the pin and at its front end against the part 76 of the yoke.

70 No difficulty will be encountered in understanding how the truck-jack is rolled into place by manipulation of the handle, its turning movements producing the steering action of the carrying-wheels at the front or opposite end of the truck.

75 The load-lifting and lowering operations occur practically as follows:—

Assuming that the truck-jack has been moved into proper position so that the saddle 42 is directly below the load, for example, 80 the axle or differential of an automobile, the operator presses downwardly with his foot on the pedal or foot-piece 52 causing a rapid elevation of the other end of the long lever 45, 46, 47, which carries the saddle or seat upwardly until the latter engages or comes up to the body or load to be lifted.

85 Such rocking of the long lever automatically swings the ratchet-segment into a corresponding position, the dogs or pawls idly riding over the teeth, but the locking dog performs its holding function when the lever reaches the height of the saddle desired.

90 Thus a quick adjustment of the saddle to the load is easily accomplished.

95 During such preliminary or initial raising of the saddle and during its further step by step elevation about to be described, the angular foot-piece 84 occupies the position shown in Figures 1, 2 and 3 with the strain 100 removed from spring 87 so that the cam-member 72 remains in the position shown in Figure 8.

To raise the load, the operator rocks 105 handle 34 up and down in a vertical plane disposed lengthwise the truck and the resulting longitudinal backward and forward movements of link 61 rock the bell-crank lever 56 and its lifting-pawl 58 in the usual way to raise the load step by step, the holding-pawl 67 performing its customary function of holding or locking the segment while the lifting-dog recedes to engage a new tooth, and idly riding over the segment teeth during the lifting turning thereof.

110 Taking for granted, that the load has thus been raised and that it is now desired to lower it step by step, the workman turns the angular foot-piece 84 forwardly with his foot thereby pulling the yoke 77 rearwardly and compressing the spring 87 between the yoke-arm 76 and the pin 86, the bar 78 passing slightly beyond dead center with respect to shaft 82, as shown in Figure 4, so that the parts will maintain the posi- 115 120 125 130

tions indicated in that figure of the drawings until released automatically or by foot as will be explained.

Such compression of spring 64 rocks cam 5 72 downwardly so that its lower end strikes the holding-dog lug 71, but the spring is not strong enough to release such holding-dog from the tooth of the segment against which it bears, because these teeth are slightly undercut and because the load imposes 10 too great a friction between the tooth and dog.

As the handle 34 is rocked downwardly, a finger 50 on the side of the pawl 58 rides on 15 the under surface of cam 72 and the pawl is thereby permitted to escape one tooth of the segment but engages the second tooth, the spring 87 acting on the cam being adequately strong to accomplish this result.

20 The cam is so shaped, however, that the lifting-dog comes into contact with the proper tooth of the segment and assumes the load, thus taking it off of the holding-dog and then the latter, under the action of the 25 spring 87 acting thereon through the end of the cam, is retracted, as shown in Figure 9, so that the reverse rocking of the handle permits pawl 58 to lower the load one full notch or tooth, but as it does so, its finger 30 or lug 50 forces the cam 72 over to allow the locking-dog to again come into play and to hold the load during the next advance movement of pawl 58.

35 Thus the load is permitted to descend step by step and, as soon as it is removed from the jack, the saddle drops automatically to its lowermost position, because we do not then have the load present to overpower the action of spring 87 and the latter is 40 strong enough under such circumstances to retract both pawls permitting the segment to rock freely allowing the load lever to descend to its lowest position as shown, for example, in Figure 2.

45 So long as the load is imposed on the saddle, there is no danger of the latter descending except slowly step by step by the rocking action of the handle 34.

50 Just before the lever bar 47 reaches its lowermost position, its top edge strikes the abutment 85 and restores the foot-piece 84 and its associated trip mechanism to load-lifting relation, the spring 87 quickly accomplishing this result just as soon as bar 55 78 passes the dead center of shaft 82, whereby the jack is again ready to raise a load without attention on the part of the operator to the tripping appliance.

60 If, after the load has been partly lowered, it becomes desirable to raise it again, this can be easily brought about, without fully lowering the load, by merely turning the foot-piece 84 by foot to lifting position, all as will be readily understood.

65 While only one embodiment of the in-

vention has herein been presented, it is to be understood that it is susceptible of a variety of embodiments differing from one another in more or less radical degree, but all incorporating the essential principles of 70 construction as defined by the appended claims.

In other words, many minor mechanical changes may be made in the appliance illustrated and described without departure from 75 the heart and essence of the invention and without the sacrifice of any of its substantial benefits and advantages.

We claim:

1. In a jack, the combination of load-engaging means, a movable handle, operating means between said handle and load-engaging means permitting said handle to raise or lower said load-engaging means, foot-actuated means to cause said operating means 80 to assume its load-lowering condition, and means to restore said operating means automatically to load-lifting relation after having been in load-lowering condition.

2. In a jack, the combination of load-engaging means, a movable handle, operating means permitting said handle to raise or lower said load-engaging means step by step, means enabling the operator to preliminarily raise said load-engaging means quickly 90 to the load without resorting to the step by step movement, and means actuated by said preliminary-raising means to restore said operating means automatically to load-lifting relation after having been in load-lowering condition.

3. In a jack, the combination of a load-engaging means, a movable handle, operating means permitting said handle to raise or lower said load-engaging means step by 100 step, means enabling the operator to preliminarily raise said load-engaging means quickly to the load without resorting to the step by step movement, and means actuated by said preliminary raising means to restore said operating means automatically to load-lifting condition when said load-engaging means approaches its lowermost position.

4. In a jack, the combination of load-engaging means, a movable handle, operating means permitting said handle to raise or lower said load-engaging means including a trip-mechanism constructed to be shifted beyond dead-center to effect the load-lowering operation, means actuated by the operator to move said trip-mechanism to load-lowering condition, and means to move said trip-mechanism back past dead-center automatically into load-raising position when the load-engaging means approaches its lowest 120 position.

5. In a jack, the combination of load-engaging means, a movable handle, operating means permitting said handle to raise or lower said load-engaging means including 130

- a trip-mechanism adapted to be actuated by the operator to selectively govern the action of said operating means whereby to cause the latter to raise or to lower the load, means to maintain said trip-mechanism in load-lowering relation after having been shifted by the operator into such condition, and
- means to automatically shift said trip-mechanism to load-raising relation when said load-engaging means approaches its ¹⁰ lowermost position.

GAILARD E. WEAVER.
ALBERT R. SQUYER.
